United States Patent Office

Des. 213,013
Patented Dec. 24, 1968

213,013

LAWN ORNAMENT

Arthur F. Klingberg, 3923 W. Main St.,
McHenry, Ill. 60050

Filed Apr. 3, 1968, Ser. No. 11,295

Term of patent 3½ years

(Cl. D35—1)

The dominant features reside in the solid line portions.

I claim:

The ornamental design for a lawn ornament, as shown and described.

UNITED STATES PATENT OFFICE
CERTIFICATE OF CORRECTION

Design No. 213,013

December 24, 1968

Arthur F. Klingberg

It is certified that error appears in the above identified patent and that said Letters Patent are hereby corrected as shown below:

In the grant, lines 1 to 3, "Arthur F. Klingberg, of McHenry, Illinois," should read -- Arthur F. Klingberg, McHenry, Illinois, assignor to Janler Plastic Mold Corporation, of Chicago, Illinois, a corporation of Illinois, --; line 13, "Arthur F. Klingberg, his heirs" should read -- Janler Plastic Mold Corporation, its successors --. In the heading to the drawings and printed specification, lines 3 and 4, "3923 W. Main St., McHenry, Ill. 60050" should read -- McHenry, Ill., assignor to Janler Plastic Mold Corporation, Chicago, Ill., a corporation of Illinois --.

Signed and sealed this 24th day of March 1970.
